(57) **CLAIM**

The ornamental design for a lottery ticket game device, as shown and described.

DESCRIPTION

FIG. 1 is a front perspective view of a lottery ticket game device showing our new design;

FIG. 2 is a top side elevational view of the lottery ticket game device shown in FIG. 1;

FIG. 3 is a front plan view of the lottery ticket game device shown in FIG. 1;

FIG. 4 is a right side elevational view of the lottery ticket game device shown in FIG. 1;

FIG. 5 is a bottom side elevational view of the lottery ticket game device shown in FIG. 1; and,

FIG. 6 is a left side elevational view of the lottery ticket game device shown in FIG. 1.

The broken lines are for environmental purposes only and form no part of the claimed design.
